MOP

Filed July 14, 1930

UNITED STATES PATENT OFFICE

ANNA HARDER, OF IDAHO FALLS, IDAHO

MOP

Application filed July 14, 1930. Serial No. 467,868.

This invention relates to new and useful improvements in mops and has for the primary object, the provision of a device of the above stated character, which includes means for removably securing a plurality of cloths or rags thereto, to form a very efficient mop or cleaning device, that may be easily handled and which will permit the cloths or rags to be removed and substituted by others 10 or washed and replaced, consequently rendering the device highly sanitary and one that may be used at a very low cost.

Another object of this invention is the provision of a head having cloth or rag- 15 receiving slots provided with serrated walls adapted to bite into the cloths or rags for firmly attaching them to the head and which will permit the easy removal or replacement of the rags when desired.

20 A further object of this invention is the provision of a novel means of attaching the handle to the head, which will permit the handle to swing relative to the head in opposite directions while mopping and allow 25 the head to always assume a proper position relative to the surface being cleaned or mopped.

A still further object of this invention is the provision of a mop of the above stated 30 character which will be simple, durable and efficient, and which may be manufactured and sold at a comparatively low cost.

With these and other objects in view, as 35 will become more apparent as the description proceeds, the invention consists in certain novel features of construction, combination and arrangement of parts as will be herein-after more fully described and claimed.

40 For a complete understanding of my invention reference is to be had to the following description and accompanying drawings in which:

Figure 1 is a vertical sectional view illustrating a mop constructed in accordance with 45 my invention.

Figure 2 is a plan view partly in section illustrating the same.

Figure 3 is a plan view illustrating the 50 blank for attaching the handle to the head.

Figure 4 is a sectional view taken on the line 4—4 of Figure 2.

Referring in detail to the drawings, the 55 numeral 1 indicates the head of a mop which may be of any desired shape and to provide a clear understanding as to the construction and operation of the invention, I have elected to show the head 1 of circular formation however the head may be any shape without altering any of the detailed construction or operation of the device. The head 1 includes a plate 2 having the edges rolled upon 60 itself to form a bead 3 over which the cleaning elements 4 are draped and which is adapted to aid in preventing the head from marring or scratching the surfaces of objects when contacted therewith. A plurality of 65 arcuate shaped slots 5 are formed in the plate 2 adjacent to the bead 3 and have their inner 70 walls serrated to form teeth 6 adapted to bite into the cleaning elements 4 when drawn through or positioned in the slots as clearly shown in Figure 2. The cleaning elements 4 are preferably in the form of rags or cloths which are drawn through the slots 5 and held 75 therein by the teeth 6 biting into the rags or cloths when the latter are draped over the bead 3 as shown in Figure 2. By moving the 80 cloths or rags out of engagement with the teeth 6, they may be easily drawn through the slots for the purpose of removing them from the head for cleaning or washing or for substitution for other rags or cloths; therefore it will be seen that a device has been provided 85 wherein rags or cloths may be easily attached and detached from the head as desired and thereby provide a device of a highly sanitary nature.

A pair of spaced brackets 7 are suitably 90 secured to the plate 2 and are substantially semi-circular in cross section and provided with inclined top walls as shown at 8 to engage corresponding walls of an attaching member 9 secured to one end of a suitable handle 10. The attaching member 9 is provided with a curved wall 11 adapted to bear against the plate 2 and cooperates with the oppositely inclined portions that contact with the inclined walls 8 of the brackets in 95 hinging the handle 10 to the head 1 of the 100

mop and permits the handle to swing in opposite directions relative to the head 1 during the use of the device and further permits the head to rest easily upon the surface being mopped or cleaned. The attaching member 9 is constructed from a blank or single piece of material as shown in Figure 3 provided with end portions 12 and body portions 13 of elongated formation and rounded at the ends. The blank is bent upon itself intermediate its ends or between the portions 13 to form the attaching member 9 and the portions 12 are curved in semi-circular shape in cross section so that when joined, form a tubular portion to receive the handle 10, the handle 10 being secured thereto by rivets or similar fasteners 14. By referring to Figures 1 and 2 it will be noted that the attaching portion 9 is provided with oppositely disposed tapered portions fitting within the bracket 8 so that the handle can swing easily in either direction relative to the head 1.

While I have shown and described the preferred embodiment of my invention, it will be understood that minor changes in construction, combination and arrangement of parts may be made without departing from the spirit and scope of the invention as claimed.

Having thus described my invention, what I claim is:

A mop comprising a head having a plurality of slots, cleaning cloths passed through the slots, closely related teeth formed on one of the walls of the slots to bite into the cloths to detachably secure the cloths intermediate their ends to the head, and a handle on the head.

In testimony whereof I affix my signature.

ANNA HARDER.
